UNITED STATES PATENT OFFICE.

JOHN B. HUNT, OF MANSFIELD, OHIO.

APPARATUS FOR SETTING FRACTURED OR BROKEN LIMBS.

1,145,064.

Specification of Letters Patent.

Patented July 6, 1915.

Application filed June 17, 1914. Serial No. 845,535.

To all whom it may concern:

Be it known that I, JOHN B. HUNT, a citizen of the United States of America, residing at Mansfield, in the county of Richland and State of Ohio, have invented certain new and useful Improvements in Apparatus for Setting Fractured or Broken Limbs, of which the following is a specification.

This invention relates to certain new and useful improvements in apparatus for setting fractured or broken limbs, and the primary object of the invention is to provide an apparatus of the type mentioned in which the patient is permitted to freely move the fractured limb up or down, longitudinally back and forth, or laterally rotate same in a horizontal plane, as he may desire, within certain restricted bounds, without imposing strain or friction on the injured limb.

Further, the invention aims to provide an apparatus which dispenses with the weights customarily employed, and employs in lieu thereof, means which draws the fractured limb into place under a determinable pressure.

Still further, the invention aims to provide an apparatus in which the limb receiving box can be easily and quickly collapsed to permit the limb to be placed within the apparatus conveniently and with comfort to the patient.

The invention also aims to provide a structure which can be placed at any point on the supporting surface of the bed, as distinguished from devices which employ weights that require room in which to operate.

Other and further objects will be later set forth, and of themselves manifested in the course of the following description.

In the drawings: Figure 1 is a top plan view of the invention; Fig. 2 is a side elevation, partly broken away; Fig. 3 is an end elevation of the box in which the limb is placed; Fig. 4 is an end elevation of the complete apparatus; Fig. 5 is an enlarged sectional view on the line 5—5 of Fig. 4; Fig. 6 is a top plan view of the base, the box being omitted; Fig. 7 is a side elevation of Fig. 6; Fig. 8 is a section on the line 8—8 of Fig. 6; and Fig. 9 is a section on the line 9—9 of Fig. 6.

In proceeding in accordance with the present invention, a base board or plate 1, is employed, preferably reinforced at its

ends by cleats 2 and 3 which act as a means to prevent longitudinal movement of the board on the bed. A plate 4 is rigidly affixed to the base 1, and is provided with an upwardly extending stud 5, which latter projects above the top face of the base 1. An L-fitting 6 revolubly receives the stud 5 and rotates in a horizontal plane and is provided with a sleeve 7. A T-fitting 8, has a 65 stub shaft 9 which rotates within the sleeve 7, the rotatable movement of the stub shaft 9 being limited by the provision of a slot 10 formed in the sleeve 7, and a screw 11 which is connected to the shaft 9 and extends 70 through the slot 10, thereby preventing the separation of the shaft 9 from the sleeve 7.

The limb receiving box has a bottom 14 which is connected to a plate 13, the latter having a depending stud shaft 12 which is 75 rotatably received within the vertical part of the fitting 8 so as to enable the box to oscillate horizontally about the stud shaft 12. The sides 15 and 16 of the box are hinged thereto at 17, and 18, respectively to 80 allow them to be moved outwardly to the dotted line position shown in Fig. 3 so as to conveniently enable the leg to be placed within the box.

The box has an end 19 provided with a 85 vertical extension 20, to which latter a base plate 21, carrying a scale 22, is rigidly affixed. The hook 23 of the scale supports a 90 yoke 24, upon which latter a roller 25 is journaled and has a strap 26 engaged thereto, the strap having a series of apertures 27 in its free end. The opposite end of the strap 26 is connected to a bracket 28, which latter is provided with hooks 29 and 30 engaged through apertures 33 and 34 of straps 95 31 and 32 respectively. The straps 31 and 32 are engaged over and with rollers 35 and 36 journaled in slots 38 and 39 provided for their reception in the end 19 of the box. The opposite ends of the straps 31 and 32 100 extend within the box and are connected to a cuff 37 which latter is secured to the injured limb, to hold and support the latter.

For the purpose of supporting the box in a horizontal plane, a support 40 is provided 105 which support is hinged at 41 to the base board 1, and has an outwardly projecting finger 43 which engages with the free end of a leaf spring 42, which latter is secured at one end to the base board 1, and has its 110 said free end movably projecting into a cut-out portion 42' provided therefor in the

upper face of the base board 1, as depicted in Fig. 8 of the drawings. When engaged with the box as shown in Figs. 2 and 4, the support 40 will hold the box against up and down movement, and when such up and down movement is desired, the support 40, 5 is moved inwardly to the position shown in Fig. 8, in which movement the finger 45 rides over and depresses the spring 42. 10 When in vertical raised position the spring 42 acts to hold the support rigidly in position, as is obvious. Apertures 44 are provided in the sides of the box to enable a strap (not shown) to be placed there- 15 through to hold the limb within the box, and latches 45 and 46 are employed, as shown in Figs. 1, 2 and 4 of the drawings to hold the sides of the box in vertical position. For the purpose of restricting the 20 combined lateral rotatable and longitudinal movements of the box, stops 49 and 50 as shown in Fig. 2 are provided for the purpose of engaging the T-fitting 8.

In operation the sides of the box are un- 25 latched and lowered, and the injured limb is thereupon placed within the box, and secured to the cuff 37, after which the sides of the box are returned to vertical position and latched in such position. The operator 30 then grasps the strap 26 and exerts a downward pull thereon, the amount of the pull being indicated by the scale 21, the extent of pull depending upon the requirements of the special case being treated, and being 35 constantly indicated by the scale which at all times points to the pounds pressure which the limb is subjected to. The straps 26 upon the desired pull upon the leg being attained, then has one of its apertures 40 27 placed over the hook 48, so as to main- tain the desired tension on the leg. Should 45 the patient desire to move the box back and forth longitudinally, the fitting 6 which pivots upon the stud shaft 5 allows of such movement, while the stud shaft 9 within the sleeve 7 has partial rotary movement there- 50 in enabling the box to be rocked or rotated partially in a vertical plane and the box can also be oscillated longitudinally about the pivot 12, from which it will be apparent that the box which retains the limb is per- mitted to have practically a universal movement. The invention therefore is adapted to either enable the leg to be held 55 stationary by use of support 40, without

said support to allow the patient to move the leg within certain bounds without friction or strain, in cases where discomfort results from constant maintenance of the leg in one position.

What is claimed is:—

1. In a fracture setting apparatus, a base, a stud projecting up therefrom, an L-fitting journaled on the stud and having a horizontal sleeve, a T-fitting having a stud which projects in the sleeve, a pin and slot connection between the sleeve and the stud which projects thereinto to allow partial rotary movement of the last named stud, a limb receiving box, and a stud extending downwardly from the box and revolubly mounted in the upper end of the T-fitting.

2. In a fracture setting apparatus, a base, a box, means to connect the box to the base so that the box may oscillate vertically and 75 horizontally, means on the base movable into and out of engagement with the box to hold the latter against vertical oscillation, and stop means on the base to engage the first named means to restrict the extent of 80 horizontal oscillatory movement of the box.

3. In a fracture setting apparatus, a base, a member having a vertical part and a horizontal part, means to rotatably connect the vertical part to the base, a box, an element 85 having a horizontal part rotatably and slidably connected to the horizontal part of said member, means to restrict the extent of relative rotary and sliding movements of 90 said horizontal parts, a vertical part on 95 said element, and means to rotatably connect the box to said vertical part of said element.

4. In a fracture setting apparatus, a base, a member having a vertical part and a horizontal part, means to rotatably connect the vertical part to the base, a box, an element having a horizontal part rotatably connected to the horizontal part of said member, means to restrict the extent of relative 100 rotary movement of said horizontal parts, and means to rotatably connect the box to said horizontal part of said element.

In testimony whereof I affix my signature in presence of two witnesses.

JOHN B. HUNT.
